DESIGN FOR A CHAIR

Hiram N. McLellan, Shaker Heights, Ohio, assignor to The Taylor Chair Company, Bedford, Ohio, a corporation of Ohio

Application November 11, 1936, Serial No. 65,851

Term of patent 7 years

To all whom it may concern:

Be it known that I, Hiram N. McLellan, a citizen of the United States, residing at Shaker Heights, in the county of Cuyahoga and State of Ohio, have invented a new, original, and ornamental Design for a Chair, of which the following is a specification, reference being had to the accompanying drawing, forming a part thereof, wherein Fig. 1 is a perspective view of a chair showing my new design and Fig. 2 is a fragmentary section through the edge of the chair seat and skirting.

The characteristic feature of the new design is the chair seat having the unbroken skirting flush with the edges thereof and an ornamental bead at the junction of the chair seat and the skirting, as shown.

I claim:

The ornamental design for a chair, as shown and described.

HIRAM N. MCLELLAN.
